UNITED STATES PATENT OFFICE.

FREDERIC ECAUBERT, OF NEW YORK, N. Y.

CLOSURE.

942,171.

Specification of Letters Patent. Patented Dec. 7, 1909.

Application filed August 3, 1907. Serial No. 386,866.

To all whom it may concern:

Be it known that I, FREDERIC ECAUBERT, a citizen of the United States of America, and a resident of the borough of Brooklyn, 5 city of New York, county of Kings, and State of New York, have invented certain new and useful Improvements in Closures, of which the following is a specification.

The present invention relates generally to 10 a packing or closure, and has more particularly reference to a closure adapted to be used for a containing vessel whose contents is under pressure or in centrifugal motion.

It is well known that considerable difficulty is experienced in preventing leakage 15 between the cover and the vessel in centrifugal or dairy machines, even when a gasket is interposed between the cover and the vessel. This is due to the fact that the diameter of these containing vessels is considerable, therefore enormous power has to be exerted to screw the cover down tight on the gasket and vessel.

The object of this invention is to enable 25 a containing vessel of considerable diameter to be closed by a cover that will effectually prevent leakage, and without the exertion of any great amount of power.

The invention consists in the hereinafter 30 described features of construction, combination of parts and arrangement of elements.

In the accompanying drawings the invention is shown in a concrete and preferred 35 form, but changes of construction may of course be made without departing from the legitimate and intended scope of the invention.

In the said drawings:—Figure 1 is a plan 40 view of the cover or closure embodying the invention. Fig. 2 is a vertical sectional view through the cover or closure and the upper end of the vessel to which it is attached.

45 Similar characters of reference indicate corresponding parts in the several views.

1 indicates a containing vessel of any suitable construction, in the present instance circular in form. At the upper end 50 of this vessel there is provided a supporting shoulder 2 externally threaded at 3 and preferably downwardly and inwardly inclined as shown in the drawing at 4. 5 indicates the closure or cover in this instance 55 provided with an annular chamber 6

formed by the downwardly projecting outer flange 7 internally threaded to engage with the threads 3 of the supporting shoulder of the vessel, and by the downwardly projecting inner flange 12. Located in this annular chamber is a continuous gasket 8 resting on top of the supporting shoulder. Within this chamber is further located the continuous pressure distributing ring 9 which may be made of iron or other suitable material. 10 indicates a plurality of individually adjustable members shown here in the form of bolts which extend through the cover from the exterior thereof and bear against the pressure distributing 70 ring, thereby exerting pressure on the packing only.

The cover is secured to the vessel in this instance by screwing it down in the usual manner, the interior threads of the flange 7 of the cover engaging with the exterior threads of the flange 3 of the supporting shoulder of the vessel. These threads need not be continuous, but may be cut away like the thread in the breech block of a gun. 80 The cover need not be screwed down unduly tight and no effort need be made to obtain a sealed contact by turning the cover itself. The cover having been placed in position the bolts 10 are turned one after another, 85 thereby compressing the gasket 8 and adjusting the sealing contact thereof. No great amount of force is required to turn the members 10 since their diameter is comparatively small. 90

It will be noted that on account of the inclined surface 4 a pocket 11 is formed into which all the pressure exerted on the gasket tends. In this manner a more perfect sealing contact can be obtained than by attempting to screw the cover itself down tightly on the gasket and vessel. 95

The word annular as used herein is not intended to limit the invention to a circular shaped containing vessel and cover. 100

I claim:—

The combination of a vessel having an open end, a cover for closing said open end provided with substantially parallel flanges arranged to engage both the interior and exterior surfaces of said vessel and spaced apart to form an annular chamber, one of said flanges being provided with means for securing the cover in position on the vessel, a packing located in said annular chamber 105 110

in engagement with the upper edge of said vessel, a pressure distributing ring also located in said recess above and in engagement with said packing and adjustable pressure members extending through the cover from the exterior thereof and bearing upon the pressure distributing ring, said pressure members extending in a direction

perpendicular to the upper surface of the pressure distributing ring.

Signed at New York city this 2nd day of August 1907.

FREDERIC ECAUBERT.
